UNITED STATES PATENT OFFICE.

EDWARD VERNON SUMMERELL, OF NORFOLK, VIRGINIA.

SAW SET.

Application filed May 24, 1924. Serial No. 715,633.

To all whom it may concern:

Be it known that I, EDWARD VERNON SUMMERELL, a citizen of the United States, residing at Norfolk, in the county of Norfolk 5 and State of Virginia, have invented certain new and useful Improvements in a Saw Set, of which the following is a specification.

This invention relates to saw-sets and it 10 consists in the novel features hereinafter described and claimed.

An object of the invention is to provide a saw-set of simple and durable structure adapted to be used for swaging and setting 15 the teeth upon a circular saw or upon a band saw and having its parts and features so arranged and assembled that they may be readily adjusted to accommodate saws of different sizes.

20 In the accompanying drawings:

Fig. 1 is a side edge elevation of the saw-set showing the same applied to a circular saw;

Fig. 2 is a top plan view of the saw-set;

25 Fig. 3 is a transverse sectional view of the saw-set cut on the line 3—3 of Fig. 2;

Fig. 4 is a side elevation of a disk wheel used upon the saw-set;

30 Fig. 5 is a sectional view of a saw supporting shaft structure used upon the saw-set;

Fig. 6 is a fragmentary side elevation of a feeding mechanism used upon the saw-set;

35 Fig. 7 is a perspective view of a guide used upon the saw-set;

Fig. 8 is a perspective view of a pawl mechanism used upon the saw-set;

40 Fig. 9 is a perspective view of a pawl used upon the saw-set;

Fig. 10 is a perspective view of the part used in the saw-set; and

45 Fig. 11 is a perspective view of spring means used upon the saw-set and adapted to engage the teeth of the saw and adapted to hold the saw against retrograde movement when the saw is about to be moved to present the unset teeth to the active elements of the saw-set.

50 As illustrated in the accompanying drawings, the saw-set comprises a base 1 having a knee 2 fixed thereon and a knee 3 adjustably mounted thereon and adapted to be secured at an adjusted position by means of a bolt 4. A set-screw 5 is threaded through a lug provided upon the base and

engages the end of the knee 3 and may be used for shifting the knee upon the base.

A shaft 6 is journaled for rotation upon the base 1 and is provided at one end with 60 a wheel 7 having a handle 8 eccentrically positioned thereon. The wheel 7 is provided at the inner side of its hub with cam faces 9.

An ovate cam 10 is mounted upon the intermediate portion of the shaft 6. Levers 65

11 are pivotally mounted one upon the knee 2 and the other upon the knee 3. Saw-teeth

swaging dogs 12 and 13 are pivotally mounted upon the upper end of the levers 70

11. The dogs 13 and 12 are of the same design and configuration and a description 75

of one will answer for both. The dog is best shown in perspective in Fig. 10 of the

drawings, and each dog is provided with a depending flange 14 adapted to operate 75

or move in a transversely disposed groove provided at the upper end of the knee 2 or 80

3. Each dog is provided at its upper edge with a notch 15. Catch members 16 are

located between the dogs 12 and 13 and 85

are provided at points between their ends with shoulders 17 adapted to engage in the

notches 15 of the dogs 12 or 13. Coiled 90

springs 18 are connected with the lower ends of the catches 16 and connected with

the intermediate portion of the lever 11 and serve to hold the shoulders 17 of the

catches down in the notches 15 of the dogs. 95

Coiled springs 19 are connected at their outer ends with the intermediate portions 90

of the levers 11 and at their inner ends with the knees and serve to hold the lower ends

of the levers 11 toward the cam 10 upon 95

the shaft 6. Set-screws 20 are threaded transversely through the levers 11 and bear

at their inner ends against the outer side 100

of the knees and serve as means for limiting the inward swinging movement of the

lower ends of the levers 11. Lugs 21 are 105

pivoted at the lower inner portions of the levers 11 and are provided at their inner sides with journaled rollers 22 which bear

upon the periphery of the cam 10. Set- 110

screws 23 are threaded through the lower portions of the levers 11 and bear against

the lower end portions of the lugs 21 and serve as means for adjustably fixing the

rollers 22 with relation to the lower ends 115

of the levers 11. The knees 2 and 3 are

provided at their upper ends with arms 24

through which a bolt 25 passes and the said

bolt bridges the space between the inner

- surfaces of the knees 2 and 3. A stud 26 is mounted upon the base 1 and a collar 27 is adjustably secured by means of a set-screw 28 upon the said stud. An arm 29 is pivotally mounted upon the collar 27 and a spring 30 is fixed to the collar and bears against the upper edge of the arm 29 and serves to normally hold the said arm in a lowered position. A claw 31 is pivoted at 10 the outer end of the arm 29, and a spring 32 is attached at one end to the arm and bears at its other end against the upper edge of the claw and serves to hold the free end of the claw toward the teeth of the saw 33 which is positioned between the knees, as will be hereinafter explained.
- A lug 34 is pivotally mounted at the under side of the arm 29 and a set-screw 35 passes transversely through the arm and bears 20 against the upper edge of the lug 34 and serves to hold the free end of the said lug.
- A shaft 36 is pivoted for rocking movement upon the base 1 and carries an arm 37 which is provided at its end with a journaled 25 roller 38 adapted to be operated upon by the surfaces of the cam 9 when the wheel 7 is rotated whereby the arm 37 is swung, the shaft 36 is rocked, and the arm 29 is rocked by an arm 39 mounted upon the shaft 30 36. A roller 40 is journaled at the end of the arm 39 and bears against the under surface of the lug 34. Therefore as the arm 29 is rocked, the claw member 31 engages one tooth of the saw 33 and the said saw is partially rotated, as will be hereinafter explained, whereby a tooth is brought between the inner end of the dogs 12 and the said tooth is swaged to one side and out of the plane of the body of the saw.
- 40 At the time that the shaft 6 is rotated, as hereinbefore stated, the cam 10 turns about the axis of the shaft 6 and the lower ends of the levers 11 are spread with relation to each other, and the upper end of the lever 45 11 which is actuated by the keeper portion of the cam 10 is moved inwardly toward the saw and the dog 12 carried at the upper end of the said lever engages the tooth of the saw and swages the said tooth.
- 50 A bracket 41 is secured upon the fixed knee 2 and a post 42 is adjustably secured upon the bracket 41. A frame 43 is adjustably secured to the post 42 and a block 44 is mounted for movement longitudinally of the frame 55 43. A screw 45 is journaled in the frame 43 and threaded through the block 44, and by turning the said screw, the block 44 may be shifted along the frame 43. A spindle 46 is carried by the block 44 and disks 47 60 are mounted upon the spindle 46 and the saw 33 is held upon the spindle between the disk 47 as best shown in Fig. 5 of the drawing. Therefore it will be seen that means are provided for holding a circular saw in position 65 between the knees in order that the teeth

of the saw may be properly and accurately swaged.

When the device is used for setting the teeth of a circular saw, the dogs 12 only are used, and the dogs 13 are turned back to 70 the positions shown in full lines in Fig. 3 of the drawings.

When the device is used for setting the teeth of a band saw, as shown at 33' in Fig. 6, the dogs 12 are swung back and the dogs 13 are swung over the upper end of the knees 2 and 3 and assume the positions as shown in dotted lines in Fig. 3. The dogs 13 are held by the catch members 16 which are lifted and turned so that their shoulder 17 may engage in the notches in the upper edges of the dogs 13. An arm 50 is pivoted at the side of the knee 2 and a set-screw 51 is threaded through the said arm and bears against the side of the knee and serves to 80 limit the swinging movement of the arm. A rod 52 connects the lower end of the arm 50 with the lower portion of the arm 37 mounted upon the shaft 36. A head 53 is carried at the upper end of the arm 50 and a pawl 54 is pivoted upon the head. A spring 55 is secured at one end to the head 53 and bears at its other end against the upper edge of the pawl 54 and serves to hold the free end of the pawl down between the 95 teeth of the saw 33'. Thus as the shaft 36 is rocked, the rod 52 is moved longitudinally whereby the arm 50 is rocked and the pawl 54 engages the edge of one of the teeth of the saw and moves the saw longitudinally between the dogs 13. As the shaft 6 continues to rotate, the levers 11 are swung with relation to each other, as hereinbefore described, and the ends of the dogs 13 encounter the sides of the tooth which is between the said dogs and the said tooth is swaged out of the plane of the body of the saw.

Having described the invention, what is claimed is:

1. A saw-set comprising a base having a 110 knee fixed thereon, a knee adjustably mounted upon the base, levers pivoted upon the knees, dogs pivoted upon the levers and guided along the upper portions of the knees, said dogs provided on their upper edges with notches, catch members provided with shoulders engageable with the notches of the dogs, springs attached to the ends of the catch members and to the levers, a shaft journaled upon the base between the levers, and a 115 cam mounted upon the shaft and adapted to swing the levers as the shaft is turned.

2. A saw-set comprising a base having a knee fixed thereon, a knee adjustably mounted upon the base, levers pivoted upon the knees, dogs pivoted upon the levers and guided along the upper portions of the knees, said dogs provided on their upper edges with notches, catch members provided with shoulders engageable with the notches of the dogs, 125 130

springs attached to the ends of the catch members and to the levers, and means for rocking the levers.

3. In combination, a base, a shaft journaled on the base, saw-setting means operable by the shaft, a cam on said shaft, a rock-lever actuatable by said cam, a pivoted arm, a lug pivoted to an intermediate portion of the arm and engageable by the free end of the lever for rocking the arm, a set-
10 screw threaded through the arm and engageable with the lug for adjusting the same in relation to the arm and the free end of the lever, a claw pivoted on the free end of the arm for engaging the teeth of the saw, and a spring disposed between the arm and the claw to hold the said claw in resilient engagement with the teeth of the saw. 15

In testimony whereof I affix my signature.
EDWARD VERNON SUMMERELL.
